ELECTRON DISCHARGE TUBE COMPRISING A
LUMINESCENT SCREEN

Franz Hermann Bitter, Hamburg, and Karl August Bisterfeld, Hamburg-Volksdorf, Germany, assignors to Hartford National Bank and Trust Company, Hartford, Conn., as trustee

Application May 16, 1952, Serial No. 288,251

Claims priority, application Germany August 10, 1951

3 Claims. (Cl. 313—107.5)

For the at least qualitative optical indication, more particularly of the tuned position, preferably in silent tuning of wireless receivers, use is made of electron tubes comprising a luminescent screen, so-called tuning indicator tubes, which indicate when the tuned position is optimum by the width of one or more luminescent angles controlled as a function of a voltage corresponding to the mean high-frequency amplitude or by the length of a luminescent strip, so-called thermometer-like indication.

The electron beam is in this case controlled by a control grid which is wound with a variable pitch of the grid wires, or by a control cylinder, Wehnelt cylinder, which is laterally slotted in the form of a wedge, or by control rods provided parallel to the cathode.

The anode is in most cases constituted by the luminescent screen itself or is provided either in the form of one or more pins or in the form of a small plate, preferably slotted, between the control system and the luminescent screen.

In known electron tubes comprising a luminescent screen and more particularly in tuning indicator tubes having a thermometer-like indication, the disadvantage occurs that the indication has not the same accuracy, for example, with strong and weak transmitters. Consequently, two angular systems having different sensitivities are provided in the tuning indicator tube comprising luminescent sectors, which naturally requires a considerably greater exertion in assembling the tube and in the wiring thereof.

Said disadvantages may be obviated and a regular clear indication with great and small control amplitudes is possible with little structural and wiring-technical exertion in an electron tube comprising a luminescent screen and more particularly in a tuning indicator tube comprising a thermometer-like indication in which a control electrode having a locally irregular control action is provided between cathode and anode or luminescent screen if, according to the invention, the whole luminescent screen or part thereof is provided in an inclined position with respect to the axis of the cathode. In this case, the luminescent screen may also serve as an anode. However, it is alternatively possible to utilise an anode which preferably has the shape of a slotted plate and—as viewed in the direction of the electron ray—to provide thereafter an auxiliary anode which serves as the luminescent screen and which preferably has the same potential as the main anode. According to a further embodiment of the invention, the main anode and the luminescent screen may be made in one piece. By the device according to the invention it may be ensured that the indication is not linear but that, for example, for the first half of the length of the luminescent strip 10% of the control voltage for the whole length of the strip is required. Such a characteristic, which is preferably logarithmic, is particularly advantageous for use as a tuning indicator tube, since strong and weak transmitters thus provide a clearly visible indication, that is to say, that the system cannot substantially be overcontrolled.

2

Such a device comprising a luminescent screen in an inclined position furthermore has the advantage that it is possible to obtain a comparatively compact structure which may readily be incorporated even in a small electron tube, for example, a Rimlock or a Naval tube, in which the cathode is preferably provided in an inclined position with respect to the axis of the tube and the luminescent screen is well visible in a broad angle range of about 180° about the axis of the tube bulb, while embodiments hitherto known have a small range of visibility only. The tube may in practice be given any desired characteristic line by the use of a curved luminescent screen.

Furthermore, such electron tubes comprising a luminescent screen frequently involve the disadvantage that at the beginning of the indication range, short luminescent strip, the brightness of the luminescent column is small, but greatly increases towards the end of the indication range, long luminescent strip, more particularly in the part which luminesces first, the starting range. The viewing is thus very detrimentally affected. This disadvantage may be obviated if in such an electron tube, more particularly of the type in which an auxiliary anode is provided separately from the anode as the luminescent screen, the whole anode or part thereof occupies an inclined position with respect to the axis of the cathode. Substantially any desired distribution of brightness and more particularly even distribution of brightness in the luminescent strip may be obtained if the anode is made curved.

In order that the invention may be readily carried into effect, it will now be described in greater detail with reference to the accompanying drawing in which:

Fig. 1 shows an elevational view of one form of tube in accordance with the invention;

Fig. 2 is a perspective view of a part of the tube illustrated in Fig. 1;

Fig. 3 shows a modification of the tube illustrated in Fig. 1.

Referring now to the drawing, between pins 1 and 2 provided in a glass base 9 of a Rimlock tube is arranged an indirectly-heated cathode 3, of which the filament leads are not shown. The cathode 3 is surrounded by a grid 4, which is wound with a continuously variable pitch and which is connected in a conventional manner (not shown) to one of the contact pins. An anode 5, which comprises a longitudinal slot (Fig. 2) and which is made in one piece with a strip-like, luminescent screen 6 of about 10 mms. in width is connected electrically and mechanically to a contact pin 7. A small tube 8 secured to the upper end of the luminescent screen 6 contains the greater material which is vaporised in known manner when the manufacture of the tube is completed.

According to the invention, the plane luminescent screen 6 occupies an inclined position of approximately 60° with respect to the axis of the cathode 3. The plate or accelerating anode 5 is likewise provided in an inclined position with respect to the axis of the cathode in order to ensure a more satisfactory distribution of brightness in the luminescent column. The anode and luminescent screen, 5 and 6, are in this case preferably made in one piece.

Upon decrease of an initially high negative bias of grid 4, an electron current will first flow through the wide meshes of the grid to strike through the anode 5 the screen 6 which is coated with luminescent substance, so that its lower end luminesces first. In combination with a suitable choice of the variable pitch of grid 4, it may be ensured by bending, for example, the upper end 6' (Fig. 3) of the luminescent screen that the absolute indication sensitivity in the upper part of the luminescent screen greatly decreases with respect to the sensitivity in the lower part, so that with unvaried relative sensitivity

an overcontrol is substantially avoided even with a considerable increase in grid bias.

What we claim is:

1. An electrode system for a tuning indicator tube, comprising an elongated cathode having a given longitudinal axis, a wound grid electrode surrounding and concentric with said cathode, said grid having a variable winding pitch progressively decreasing in value toward one end of the cathode, an accelerating anode having an aperture therein spaced from said cathode and grid, said accelerating anode being inclined at an acute angle with respect to the axis of the cathode, and an elongated luminescent screen facing said cathode and being disposed substantially on the side of said accelerating anode remote from said cathode, said luminescent screen being aligned with the cathode and with said aperture in said anode, said luminescent screen being inclined at an acute angle with

10

respect to said axis of said cathode different from the angle of inclination of said accelerating anode with respect to said cathode, said luminescent screen being closer to the other end of said cathode than to said one end.

5 2. An electrode system as claimed in claim 1 wherein the luminescent screen is curved.

3. An electrode system as claimed in claim 1 wherein the accelerating anode is mounted on and secured to said luminescent screen.
